UNITED STATES PATENT OFFICE.

ALEXANDER GARTSHORE AND WILLIAM MAXWELL, OF PITTSBURG, PENNSYLVANIA.

SPIKE-PULLER.

SPECIFICATION forming part of Letters Patent No. 740,415, dated October 6, 1903.

Application filed December 23, 1902, Serial No. 136,338. (No model.)

To all whom it may concern:

Be it known that we, ALEXANDER GARTSHORE and WILLIAM MAXWELL, citizens of the United States of America, residing at Pittsburgh, in the county of Allegheny and State of Pennsylvania, have invented certain new and useful Improvements in Spike-Pullers, of which the following is a specification.

This invention relates to spike and nail pullers, and it has as its basis the object of producing novel means for effecting the withdrawal of spikes or nails without their being bent.

A further object of the invention is to produce a novel arrangement of parts whereby an attachment is provided for ordinary claw-hammers, whereby the pull is longitudinally of the nail, or nearly so, during the whole operation of extracting the nail.

Furthermore, the object of the invention is to produce a nail-extracting implement and in combination therewith a readily-detachable base or support in order that the base or support need not obstruct the use of the implement when the function of the base or support may be dispensed with.

Furthermore, the object of the invention is to produce a base for an implement of the character noted which is in such relation to the implement that the said base may be moved by the foot of the operator in order that it may be properly positioned with relation to the nail or spike to be extracted to attain the best results.

Finally, the object of the invention is to produce a device of the character noted which will possess advantages in points of efficiency, simplicity, and durability, proving at the same time comparatively inexpensive.

With the foregoing and other objects in view the invention consists in the details of construction and in the arrangement and combination of parts to be hereinafter more fully set forth and claimed.

In describing the invention in detail reference will be had to the accompanying drawings, forming part of this specification, wherein like characters denote corresponding parts in both views, and in which—

Figure 1 is a view in elevation illustrating a claw-bar and its support. Fig. 2 is a similar view illustrating the ordinary claw-hammer provided with a base.

In the drawings, A denotes an ordinary claw-bar, B a base-plate, and C posts formed integral with the base-plate. It will be observed that the base-plate is flat on its lower surface and that it extends a considerable distance to the front of the posts, thus affording a bearing for the foot of an operator for retaining it in a fixed position or for exerting force to slide it toward the object extracted to increase the vertical force of the claws.

As illustrated, the sides of the claw-head are cut away somewhat to form shoulders 1, and the upper portions of the shoulders are rounded, as at 2, to form bearings for the upper rounded surfaces of the posts. In this arrangement the supporting posts may be readily applied and removed and a pivotal pin is dispensed with. Hence an aperture in the claw-head need not be formed.

As shown in Fig. 2, the sides of the claws of the hammer are cut away to form shoulders 3 and a socket or seat 4 for the upper ends of the posts, and the operation and advantages of this construction correspond to the construction and operation described in connection with the disclosure of the invention illustrated in Fig. 1.

The construction, operation, and advantages will, it is thought, be understood from the foregoing description, it being noted that various changes may be resorted to in the proportions and other details of construction for successfully carrying the invention into practice without departing from its scope.

Having fully described the invention, what we claim as new, and desire to secure by Letters Patent, is—

In a device of the character described, a head or body having claws, said parts having their sides cut away to form shoulders, in such relation as to form bearings for supporting the head or body when the claws are in operation, movable posts on which the shoulders rest, on which they are trunnioned, as and for the purpose described.

In testimony whereof we affix our signatures, in the presence of two witnesses, this 22d day of December, 1902.

ALEXANDER GARTSHORE.
WILLIAM MAXWELL.

Witnesses:

JOHN NOLAND,
J. P. APPLEMAN.
